OSCILLATABLE BASEBALL GAME BOARD

Harry P. Hutchins, Audubon, N. J.

Application May 24, 1949, Serial No. 95,100

1 Claim. (Cl. 273—88)

1

This invention relates to game boards and more particularly to a board upon which a game simulating baseball may be played, and it consists in the constructions, arrangements and combinations herein described and claimed.

It is an object of the invention to provide a game board upon which may be played a game, by two contestants, sitting opposite each other, wherein the play of each is modified by the play of the other, and the playing of neither being visible to the other until both plays have been completed.

A further object of the invention is to provide a game board having oppositely positioned control means, each to be operated by a player, and each control means remaining dormant no matter how the controls may be set until the controls of both sides are set.

A further object of the invention is to provide a game board having oppositely positioned control means, with an interposed field responding to various combinations of the two control means, but failing to respond to any manipulation of the controls of a single control means without the setting of the opposed control means.

A further object of the invention is to provide a game board upon which may be played a game simulating baseball, having a field representing positions, and other elements of a baseball game, with control means respectively representing "Ins" and "Outs" both of which control means must be set to pre-elected combinations before any play is effected upon the field.

A further object of the invention is to provide a game board upon which may be played a game simulating baseball, having a field properly designated and supplied with indicia representing positions and activities with a control means for the side representing the "Outs," which said control system will enable the player to select the throw to be made (as well as to select the activities of the men in the field), while the other control means provides for activities analogous to that of a batter who will bat a ball to any pre-determined position in the field, the result of such batting depending upon the positioning and activities of the field score.

A still further object of the invention is to provide a game board upon which may be played, by two contestants, a game simulating the game of baseball, wherein every play is first mentally, and then physically pre-determined, and no play or any part of the play, depending upon chance.

Additional objects, advantages and features of invention will be apparent during the follow-

2

ing description and accompanying drawings, wherein:

Figure 1 is a top plan view of the game board;

Figure 2 is a horizontal cross section immediately above the base of the game board illustrating the pivot pins of the pitcher-fielder controls and the pivot pin for the batter control and play revealing disk;

Figure 3 is a similar view with the batter-fielder and pitcher controls installed upon their respective pivot pins;

Figure 4 is a horizontal cross section above the batter control;

Figure 5 is a horizontal section through the game board directly above the play revealing control means;

Figure 6 is a side elevation of the game board; and

Figure 7 is a section taken on the line 7—7 of Figure 1.

Attention is now invited to Figures 1, 6 and 7 of the drawings wherein there is shown a game board generally indicated by the reference character 10. The game board comprises a base board 11 of any suitable dimensions mounted upon feet 11', and supported above the board 11 by means of spacer strips 12 there is a board 13, the latter in turn having secured thereon a very thin sheet of cardboard 14 having printed thereon a baseball field 15 as well as other essential features as will be explained hereinafter.

Between the base board 11 and the board 13, the fielder, pitcher, batter and play revealing controls are operatively mounted, reference first being made to Figure 2 of the drawings, wherein it will be seen that the base board 11 is provided with opposed playing ends namely a fielder-pitcher end 16 and a batter end 17. The fielder-pitcher end bears notations "R. F.", "Pitcher," "C. F.," "S. S." and "L. F." and associated with each of the field positions there appear the words "Rest" and "Play" with indicating marks 18 and 19 cooperating with play controlling means presently to be described. Adjacent to the word "Pitcher" the legends "Good Pitch" and "Bad Pitch" appear with indicators 20 and 21 thereadjacent. Upright pins 22 are mounted in the board 11, a pair being arranged in advance of the field and pitcher notations, these pins functioning as stop means for the controlling means. Pivot pins 23, 23', 23'', 23a and 23b are also mounted in the base board, there being one for each of the field positions and the pitcher, and to one side of each of the field positions there is an indicator 24, which may be merely a colored

mark. Medially of the board 11, four symbols 25 are disclosed, to indicate a "Hit" upon proper manipulation of the control means. There are also symbols 26, 27 and 28 to indicate respectively a "Strike," "Ball," and "Foul."

The batter's end 17 embodies spaced notations "R. F.," "C. F.," "S. S.," "L. F.," and the word "Wait." Respective arrows 29, 30, 31, 32 and 33 are aligned with respective notations to indicate the position of the batter's control setting.

The board 11 is formed with an aperture 34 at a suitable point between the ends 16 and 17 through which an assembly bolt 35 is disposed, the bolt also mounting certain play controlling means, presently to be described.

Reference is now made to Figure 3 of the drawings, wherein it will be seen that upon each of the pivot pins 23, 23', 23'' and 23b an oscillatable play indicator 36 is mounted, each indicator having an "O" depicted thereon at such positions as to correspond with the locations of respective "Hit" symbols 25 on the board 11. The "Pitcher" indicator 37 is oscillatable upon the pivot pin 23a and has a rectangular shutter member 38, within which there is formed a "Foul" slot 39 and a "Ball" slot 40 so located as to register with the strike indication 26, the ball indication 27 and the foul indication 28 on the board 11 under certain movement of the shutter as will be explained. Since the shutter 38 must pass inwardly toward and beyond the assembly bolt 35, an arcuate slot 41 is formed in the adjacent edge of the shutter.

Mounted on the assembly bolt 35 there is a circular disc 42 (see Figure 4), suitably spaced above the board 11 and the indicators 36 and 37, by means of a washer 43. This disc will be termed the "Batter" disc since it is employed to modify or determine the play of the setting of the fielders and pitcher indicators 36 and 37. The disc has an upstanding knob 44 for readily rotating it to selected positions of "R. F.," "C. F.," "S. S.," "L. F." and "Wait." An indicator line 45 is provided on the disc so as to insure proper positioning of the disc to a desired play indicated by the reference characters 29 to 33. The disc 42 is further formed with openings 47 and 48, the opening 47 adapted to register with the "Strike" notation 26 and the "Ball" notation 27 on the board 11 and the slot 48 is adapted to register with the foul slot 39 of the shutter 38 under varying positioning of the pitcher indicator 37. Inwardly of the periphery of the disc 42 openings 49, 50, 51 and 52 are formed adapted to register with the "Hit" notations 25 on the board 11 or with the "Out" notations carried on the play indicators 36. A play revealing disc 53 is rotatably supported upon the pin 35, spaced above the batter disc 42 by means of a washer 54, and as may be seen in Figure 5 is formed with an eccentric portion 55 occupying a position adjacent the batter's end 17 of the game board and an enlarged portion 56 concentric with the pin 35, adjacent the pitcher's end of the board. Openings 57 and 58 are formed through the eccentric portion 55 of the disc adapted to register respectively with the "Strike" and "Ball" opening 47 of the disc 42 to expose the notation 26 or 27 on the board 11, which will depend upon the setting of the pitcher indicator 37. A foul opening 59 is also formed through the disc 53 adapted to align with the slot 48 of the disc 42 to expose the "Foul" notation 28 on the board 11. Additional openings 60, 61, 62 and 63 are provided in the play revealing disc 53 complementary to the

"Hit" notations 25 on the board 11. Openings 64, 65, 66, and 67 are also formed in the disc 53 so positioned as to expose the play indicator 24 on the board 11.

5 A washer 68 is positioned upon the bolt 35 for support and spacing of combined cover and shield board 69, the cover portion thereof being formed with openings 57', 58', 59', 60', 61', 62', 63', corresponding to openings 57 to 67 of the play revealing disc 53.

10 In order that the selection of plays may not be known to either of the players, the board 69 is scored along parallel longitudinal lines to form respective shields 70 which may be moved to vertical positions as clearly shown in Figures 1, 15 6 and 7. Any suitable means may be employed for supporting the shields 70 in their operative positions and in the present instance, a tongue 71 is formed at respective ends of the shields, bent rearwardly to rest upon the base board 11. When the shields 70 are in their upright operative positions the pitcher-field and batter ends 16 and 17 are exposed to the view of each respective player, but concealed to his opponent.

15 The board 69 is formed with an arcuate slot 72 through which a handle 73 may project, the latter being connected to the play revealing disc 53 for moving said disc to open and closed positions.

20 The cover 14 bearing the notation of a baseball diamond is also formed with openings corresponding to the openings formed in the combined cover and shield, as will be readily understood.

25 While the bolt 35 secures the game boards and operative discs in assembled relation, additional bolts 35' are employed to secure the base board 11 and top board 14 together.

Procedure of play and results

30 The pitcher indicator 37 may be set for either a "Good Pitch" or a "Bad Pitch" and the batter may "Wait" if he anticipates a "Bad Pitch" or he may "Hit" if he expects a "Good Pitch." Thus, if the pitcher indicator 37 is moved to the notation "Good Pitch" and the batter has moved the batter disc 42 to the "Wait" position the "Strike" notation 26 will appear at the aligned strike openings; but if the pitcher elects to move his indicator 37 to the "Bad Pitch" notation, and the batter has his disc set on the "Wait" notation, a "Ball" indication will appear in the aligned ball openings.

Pitcher, batter and fielder operations and results

35 If the pitcher moves his indicator 37 to the position of "Good Pitch" and the fielder indicator 36 is set to play left field, while the batter has moved his disc to play left field, the result will be indicated as an "Out" in the opening 61' by reason of the fact that the "Out" symbol on the left field, indicator 36 had been moved to align with the opening 49 of the disc 42. However, if the fielder had not played left field the result would have been a "Hit" since the hit symbol 25 would be exposed in the opening 49 as well as the aligned opening 61'. In the event that the pitcher indicator 37 is set for a "Bad Pitch" instead of a "Good Pitch" as previously stated, and the fielder indicator 36 plays left field, and the batter has his indicator 45 set on the left field position, the result will be indicated as a "Foul" due to the fact that the pitcher indicator 37 was moved to the full line position shown in Figure 3, with the foul opening 39 aligned with the 40 foul symbol 28, and also the "Out" symbol at left

field would be exposed, representing a combined "Foul-Out," which would be the logical result from a "Bad Pitch." However, if the fielder had not played left field, the result would still be indicated as a foul, and in addition, by reason of the fact that the left field indicator 36 would be in the dotted line position shown in Figure 3, or at "Rest" the "Hit" symbol 25 would be exposed, resulting in a combined "Foul-Hit" and charged against the batter as a foul strike. The same results will be attained at the other three fields, namely "R. F.", "C. F." and "S. S."

The start of a game will involve the shields 70 set in upright positions, so that neither of the players may see the moves made by the "Pitcher-Fielders" or the "Batters" setting. The field indicators 36 must be at "Rest" position and the pitcher indicator 37 at the "Pitcher" position. The handle 73 is moved to open position as clearly shown in Figure 1, moving the play revealing disc 53 so as to properly position the openings therein with symbols on the disc and on the board 11. The pitcher indicator 37 is the first to be moved, either to "Good Pitch" or to "Bad Pitch" and in Figure 1, the "Good Pitch" has been elected. The fielder now moves two of his indicators 36 to elected position, here shown as "L. F." and "R. F." at the "Play" position. When these indicators were so moved, the colored indicators 24 are exposed through openings 61' and 63' representing the plays which have been made in the field and these would be visible to the batter, so that he may know that only two elections have been made. The batter now moves his disc 42 to an elected position, namely "Left Field" which would result in the plays as previously described.

From the foregoing, it will be seen that a "Good Pitch" will always result in a strike when the batter "Waits" and will always result in a "Hit" or "Out" when hit by the batter.

A "Bad Pitch" will always result in a ball when the batter "Waits" and will always result in a "Foul Out" or a "Foul Hit" when hit by the batter. A foul is charged against the batter as a foul strike and a "Foul Out" is charged as an "Out."

Rules

The fielder may play no more than two fields at one time.

If after plays have been selected and the play revealing disc has been moved to open position to disclose the plays selected, if the play indicator reveals more than two fields played by the fielder, this particular kind of play is not to be allowed.

A foul hit is a strike charged against the batter, except that it cannot be considered a third strike.

A foul out is an out charged against the batter.

A fair hit to "S. S." is a one base hit; "R. F." is a two base hit; "C. F." is a three base hit; and "L. F." is a home run.

Any other rules may be those of a regular base ball game.

From the foregoing, it will be seen that a game has been provided wherein the simulated game of base ball may be carried out and while I have shown and described a preferred construction thereof, this is by way of illustration

only, and I consider as my own all such modifications in construction as fairly fall within the scope of the appended claim.

What I claim:

5 A game board comprising a base member having a pitcher-fielder end and an oppositely positioned batter end, said pitcher-fielder end having notations "R. F." and "Play"; "Bad Pitch"; "Pitcher"; "Good Pitch"; "C. F."; "Play"; "S. S." and "Play" and "L. F." and "Play"; said batter end having notations "R. F."; "C. F."; "S. S."; "L. F." and "Wait," a fielder indicator oscillatably mounted on said base member, there being one for each field position, a pitcher play indicator oscillatably mounted on said base and complementary to said pitcher notation, said base having a "Hit" notation for each fielder indicator to be concealed by respective indicators when moved to the "Play" position, and exposed when moved to the field designation, each fielder indicator further having an "Out" notation positioned to align with the "hit" notation on the base when moved to the "Play" position; said base further having notations representing a "Strike"; a "Ball" and a "Foul", said pitcher play indicator having a slot to expose the "Foul" notation and further having a slot to expose the "Ball" notation, and cover the "Strike" notation when said pitcher play indicator is aligned with the "Bad Pitch" notation, said "Ball" notation being covered and said "Strike" notation being exposed when said pitcher play indicator is moved to "Good Pitch" position; an upright pin mounted in the medial portion of said base, a batter control member rotatable on said pin and positioned above said fielder and pitcher indicators, said batter control having openings positioned to align with the "Hit" notations on the base and with the "Out" notations on the fielder indicators at times; said batter control further having formed therein a "Strike"; "Ball" and "Foul" slot adapted to register with corresponding notations on the base, upon selected plays between the fielder, pitcher indicators and the batter control, a play revealing disc oscillatably mounted on said upright pin above the batter control and having slots adapted to align with the slots of said batter control in one position of its movement, said play revealing disc further having openings arranged to register with indicia on the base for revealing the play position of the fielder indicators, and a top member on said upright pin above the play revealing disc and fixed to said base, said top member having slots in registry with the slots of the play revealing disc and having a vertically disposed shield member in advance of the pitcher fielder end and said batter end.

HARRY P. HUTCHINS.
